WATER SHEDDING DEVICE FOR WASHING MACHINES AND THE LIKE

Filed March 19, 1930

UNITED STATES PATENT OFFICE

JOHN MIKULASEK, OF NEWTON, IOWA, ASSIGNOR TO THE MAYTAG COMPANY, OF
NEWTON, IOWA, A CORPORATION OF DELAWARE

WATER SHEDDING DEVICE FOR WASHING MACHINES AND THE LIKE

Application filed March 19, 1930. Serial No. 437,248.

The present invention relates to water shedding devices and more in particular to such novel device associated with the driving means in a washing machine.

- 5 Among the objects of the invention is to provide novel means in a washing machine for preventing leakage of water from the interior of the machine into the driving means therefor and/or diverting, deflecting 10 and draining any water which may have seeped or leaked into the housing for said means and prior to its having become mixed with the lubricant packed about movable parts of said driving means.
- 15 The invention comprehends the idea of providing a novel means for journalling the upper portion of a drive shaft for a gyratator or other agitating means of the washing machine and in a housing for said drive shaft, 20 which bearing prevents any substantial leakage of water from the machine into the housing and which would seep or flow into the driving mechanism of the shaft, as likewise, to provide novel means for deflecting, divert- 25 ing and draining any water which may have passed said journalling means before the same may enter the housing of the drive shaft mechanism and to drain the same by way of a passage or the like from the interior of said 30 shaft housing to the exterior of said machine.

In the specific embodiment selected to illustrate the novel invention, the gyratator drive shaft is provided with a housing in which is mounted at the upper part thereof, a novel 35 bearing, to be more fully described, below which and associated with the shaft and housing are two overlapping members. One of these members is mounted on the shaft 40 and is provided with a skirt portion overlapping a gland member mounted in the housing and which has a part fitting about the shaft and pressing against a packing mounted on said shaft. The shaft housing is provided 45 with an opening adjacent these members and which communicates with the exterior of the machine. Any water which may have seeped or leaked through the bearing is deflected by way of these members to the opening and 50 thence to the exterior of the machine without

having entered the housing of the driving mechanism of the drive shaft.

Other objects, advantages, capabilities and features are comprehended by the invention as will later appear, and as are inherently possessed thereby.

Referring to the drawing:

The figure is a fragmentary view in vertical cross section of a washing machine showing an embodiment of the invention associated with the drive shaft and housing of the same.

Referring now more in detail to the drawing, the embodiment selected to illustrate the invention is shown as being associated with a gyratator or agitator drive shaft 1 of a washing machine 2 having a tub 3 of any desired construction. The tub 3 at the bottom thereof is provided with a central plate 4 fitting in an opening in the tub and connected therewith by any suitable means, this plate being provided with an upstanding annular flange 5 for supporting a gyratator or agitator 6, and in which is pressed or mounted a tubular housing 7 adapted to enclose the shaft 1.

The upper end of the drive shaft 1 is journalled within a bearing member 8 (to be more fully disclosed) which in turn is mounted in the upper end of the sleeve 7, this shaft extending upwardly and beyond the bearing member and having a non-circular driving element 9 secured thereon as by way of a pin 10 or the like. The driving element 9 is adapted to be received in and drive a member 11 coupled therewith which is pressed in or mounted in the end of a tubular housing 12.

This tubular housing 12 extends downwardly and encloses the drive shaft housing 7, which is provided with an annular collar 13 pressed or mounted over the lower portion thereof, this collar being adapted to provide bearing for the lower end of said tubular housing 12 when same is in operative position for operating the gyratator or agitator 6. The gyratator 6 is provided with a hub 14 adapted to be mounted on the lower end of the tubular housing 12 and to be operated therewith.

The lower end of the shaft 1 is journaled in a bearing 15 in a housing 16 which is suitably secured to the central plate 4 and which encloses mechanism (not shown) for oscillating a sector 17 having teeth meshing with the teeth of gear 18. This gear has integral therewith a clutch element 19, a bushing 20 being fitted within a longitudinal bore thereof for loosely mounting this integral structure on the shaft 1.

Another clutch element 21 having a hub 22 is provided and is secured to the shaft 1 by means of a pin 23 or the like. A bifurcated arm or shifter 24^a is provided for slidably moving the clutch element 19 into and out of engagement with the clutch element 21 for operating the drive shaft 1 and gyratator 6. The mechanism for driving the shaft 1 and enclosed within the housing 16 is packed in grease or other suitable lubricant and it is important that no water or moisture enter the same.

Although the novel bearing 8 (to be later described) will prevent substantially all leakage or seepage of water from within the tube 3 into the mechanism within the housing 16, further means are provided to shed and drain any water which may have found passage therethrough and between the shaft and the same.

Such means comprise an upper member 24 having a hub portion 25 mounted on the shaft 1, the upper end thereof being bent inwardly to provide an annular part 26 adapted to engage in the annular groove or channel 27 of the shaft 1, for securing the member thereon. The lower part of this member 24 is flared outwardly to provide a skirt or hood portion 28 which is spaced from a lower member 29 and overlapping the same.

This member 29 has an annular part pressed or mounted in the sleeve 7, while the upper portion thereof slopes inwardly to form a frustum-shaped or conical part 30, the upper edge thereof fitting about the shaft 1 and being beneath the hood or skirt portion 28. The upper part 30 of the member 29 serves as a gland member for holding a packing 31 from movement, the packing being around the shaft and bearing or resting on the end of the hub 22 of the upper clutch member. Although I have shown a clutch member adjacent the packing 31, it is to be understood that other suitable means may be provided upon which this packing may rest and be held from longitudinal movement along the shaft 1, should it be desired to dispense with the clutch elements 19 and 21 and substitute therefor other suitable driving means for this shaft.

An aperture 32 is provided in the lower end of the tube 7 and adjacent the lower member 29 and which registers with an elongated passage 33 in the central plate 4, this opening or aperture 32 and passage 33 providing means for draining water which may have leaked

past the bearing 8, and which is deflected and diverted from its downward passage within the housing 7 to the exterior of the machine, where it may be collected, if desired, or allowed to drip onto the ground or floor. It will therefore be seen that any water which may enter the housing 7 will be prevented from entering or passing into the housing 16 to dilute and mix with the lubricant within the housing 16 and surrounding the mechanism therein.

The bearing 8 for journaling the upper part of the shaft 1 comprises a cage or the like 34 having a longitudinal bore into which is pressed or mounted upper and lower bushing sections 35 and 36, which bushings are of a porous material or composition, such as graphite bronze or the like. The cage or outer supporting member for the bushings has enlarged end parts 37 and 38 which may be pressed or mounted within the tubular housing 7 for providing a substantially rigid journal for the shaft and to provide an annular chamber thereabout and between the same and the tubular housing 7.

The cage 34 has strips, such as 39 extending between the enlarged ends 37 and 38 and on opposite sides thereof to provide an integral bearing structure. The strips 39 are connected together by lugs or projections 40 and 41 on opposite sides of the cage and project outwardly into the chamber, in between which and the ends 37 and 38 are openings to the bushings 35 and 36. These projections contact with a wick 42 which lays against the tubular housing 7 and which is seated in an annular groove 43 in the lower enlarged end 38 for maintaining this wick in an upright position.

Lubricant, such as oil or the like is introduced into the annular chamber by way of an opening or bore 44 in which is secured a spring pressed plunger 45 or other suitable means whereby the lubricant in the chamber may be replenished and which will prevent leakage of the same therethrough. The oil supplied to the chamber is absorbed by the wick and is likewise absorbed by the porous bushing sections 35 and 36 for properly lubricating the shaft 1 journaled therein.

This bearing likewise prevents any substantial leakage or seepage of water from the washing machine downwardly through the housing 7 and into the mechanism within the housing 16. Should there be any leakage, however, the shedding means provided within the housing 7 and associated with the shaft 1 and housing 7 and as hereinbefore set out will prevent any of such water from entering the housing 16.

While I have herein described and upon the drawing shown an illustrative embodiment of the invention, it is to be understood that the latter is not limited thereto, but may comprehend other constructions, details, ar-

rangements of parts, and features without departing from the spirit thereof.

Having thus disclosed the invention, I claim:

5 1. In a washing machine provided with an agitator, a tubular member mounted in the tub of said machine and having a passage communicating with the exterior thereof, a drive shaft for said agitator, and means associated with said shaft and member for deflecting water from said member through said passage.

10 2. In a washing machine provided with an agitator, a drive shaft for said agitator, a housing for said shaft and having an opening communicating with the exterior of the machine, and a member carried in said housing and fitting about said shaft for deflecting water entering said housing to said opening.

15 3. In a washing machine provided with an agitator, a drive shaft for said agitator, a housing for said shaft and having an opening communicating with the exterior of the machine, a member carried by said housing and fitting about said shaft, and a second member mounted on said shaft overlapping said first member, said opening adapted to receive water entering into said housing and passing over said members.

20 4. In a washing machine provided with an agitator, a drive shaft for said agitator, said shaft having an annular groove, a housing for said shaft and having an opening communicating with the exterior of the machine,

25 a member pressed into said housing and having a part fitting about said shaft, a second member mounted on said shaft and having parts engaging in said groove, said members adapted to deflect water entering into said

30 housing to said opening.

5. In a washing machine provided with an agitator, a drive shaft for said agitator, a housing for said shaft and having an opening communicating with the exterior of the machine, a water deflecting member carried by

said housing, and a packing around said shaft, said member having a part fitting over said packing and about said shaft.

6. In a washing machine provided with an agitator, a drive shaft for said agitator, a housing for said shaft and having an opening communicating with the exterior of the machine, a packing around said shaft, a gland member carried in said housing and fitting over said packing and about said shaft, and a second member mounted on said shaft and overlapping said gland member.

7. In a washing machine provided with an agitator, a drive shaft for said agitator, said shaft provided with an annular groove, a housing for said shaft and having an opening communicating with the exterior of the machine, a packing around said shaft, a gland member mounted in said housing and fitting over said packing, and a second member mounted on said shaft, said second member having a part engaging said groove and a skirt portion overlapping said gland member.

8. In a washing machine provided with an agitator, an agitator supporting member, a shaft for said agitator, a housing for said shaft mounted in said support and provided with an opening, said support having a passage registering with said opening and leading to the exterior of the machine, and deflecting means associated with said shaft and housing for deflecting water within said housing to said passage.

9. In a washing machine having a tub and provided with an agitator therein, a drive shaft extending through the bottom of the tub and operatively connected for driving the agitator, a housing for said drive shaft and provided with a passage communicating with the exterior of the machine for draining away water entering into said housing, and deflecting means for deflecting water away from said shaft and towards said passage.

JOHN MIKULASEK. 110
